UNITED STATES PATENT OFFICE

2,249,652

ALBUM

Don M. Harris, Alhambra, Calif.

Application February 13, 1940, Serial No. 318,675

1 Claim. (Cl. 129—19)

This invention relates to albums, binders, scrap books and the like.

The principal object of my invention is to provide a flat opening album or binder with leaf holding means that permits expansion or contraction. Another object is to make such an album of such simple loose-leaf construction that the manner in which leaves may be added to or removed therefrom will be obvious to an ordinary layman.

A still further object is to make said album of such materials and parts as can readily be formed or cut into the desired shape, and that are of moderate cost, and are durable.

The foregoing and other objects which will appear as the nature of the invention is better understood, may be accomplished by a construction, combination and arrangement of parts such as is disclosed by the drawing and specification. The nature of the invention is such as to render it susceptible to various changes and modifications, and, therefore, I am not to be limited to said disclosure; but am entitled to all such changes therefrom as fall within the scope of my claim.

In the drawing:

Figure 1 is a plan view of my album in open position, partly broken away to better show a leaf holding member.

Figure 2 is a sectional view taken on the lines 2—2 of Figure 1.

Figure 3 is a perspective view of my leaf holder.

Figure 4 is a detail sectional view showing a leaf being put into my leaf holder and another leaf already in place therein.

As illustrated, my album or binder has a top cover 7 and a bottom cover 8, each of which has a binding portion 7a and 8a, at the left edge thereof jointed thereto at 9. This permits the main portions of said covers 7 and 8 to be moved to open or closed position while said binding portions 7a and 8a can remain in their position. The join 9 permitting this movement is reinforced by covering it with a strip of material 10 such as cloth as shown. Both covers 7 and 8 have holes 11 in their said binding portions 7a and 8a to permit the usual telescopic posts 13 or screw posts, to extend therethrough.

I provide leaf holders 15 of any desired color which consist of a flat supporting or main anchorage portion 16 which extends between the upper and lower edges of my album and which is preferably about the same size as said binding portions 7a and 8a, or a little wider. Extending from said supporting piece 16 are a plurality of sheet-holding tabs or arms 17, a portion of each

said arm 17 being formed into a loop or arcuate portion 18 in which the leaves 25 of my album are retained, and are readily movable therein. Beyond said loop 18 is an end portion 19 which extends over said supporting piece 16, because said arm 17 has been turned back upon itself as shown. By scoring said arm 17 as at 20 just beyond said supporting piece 16, and again scoring it, as at 21, at a more distant point, said loop 18 is formed between said scores 20 and 21 in a simple manner. Said leaf holders 15 may be made of a flexible sheet material such as Celluloid, plastic, or thin metal, and said supporting piece 16 has holes 22 therein which correspond with said holes 11, and through which said telescopic posts 13 extend. To hold said free end portions 19 in place some of them may be provided with holes as at 23 and said posts 13 will extend therethrough so that said leaf holder will be held evenly in position.

The leaves or sheets 25 which my binder or album is made to hold consist of the usual sheets or leaves 25 of paper or thin cardboard, and at their left side a plurality of thin slots 26 are cut therein that are spaced only a short distance from the left edge of said sheets. Said slots 26 correspond with said arms 17, being slightly larger to permit the free end portions 19 and loops 18 of said arms to be readily inserted thereinto and to provide for movement of said leaves 25 in said loops 18. Each said leaf holder 15 can receive a desired number of said leaves or sheets 25, such as twelve, and any leaf can be removed by sliding it and any leaf above it off said leaf holder 15, putting back the leaves 25 desired to be kept in the album. The leaves 25 normally rest in said loop or arcuate portion 18 and can freely move from open to closed position therein. Thus it will be seen that this album has the advantages of loose-leaf binding, and said leaves 25, when the album is opened, will lie flat.

One or more leaf holders 15 may be used in my album, and between said leaf holder a spacer member 28 is placed, which rests directly on said free end portion 19 which lies flat on said flat supporting piece 16. These spacer members 28 may be made of fiber, wood or other suitable material, and they have holes 29 therein to correspond with said holes 11 and 22 and 23, through which said telescopic posts 13 extend. There is a spacer member 28 that lies flat against said bottom cover binder portion 8a and another said spacer member at the top of the assembly of leaf holders that is directly below said top cover binder portion 7a. As pictures or other things are

affixed to said sheets 25 their thickness is increased, and the spacer members 28 serve to provide sufficient space between one said supporting piece 16 and another, so that the sheets 25 can be turned over freely even though they occupy considerably more space as they are increased in number or thickened as by pasting photographs or papers on them.

The whole assembly is fastened together preferably by a cord 30 which extends through said telescopic posts 13, and the end portions of which are tied or otherwise connected together as indicated at 31. As will be seen, it is a simple matter to remove one or more leaves 25 or add to them, or add to the number of leaf holders 15 and spacers 28 by merely untying said cord 30, taking the top cover 7 off, removing whichever said spacers 28 and leaf holders 15, as is necessary, or adding to them, as desired. Said leaves 25 can readily be slipped over said end portions 19 to remove them, or new sheets can easily be inserted in place by inserting said end portions 19 through said slots 26.

In this construction any part of my album can be opened thus presenting any single sheet 25 desired in substantially flat, visible position. It is adaptable to hold bookkeeping records and other

papers in a loose-leaf form and so they can be opened to flat position.

What I claim is:

An album comprising a bottom cover, a top cover, each said cover having a binding portion at one side, the remainder of each said cover being movable relative to said binding portion from closed to open position, said binding portions having holes therein, leaves between said covers each having slots at a side portion thereof, a plurality of leaf holding members between said covers, each embodying a supporting portion lying between said binding portions, and having a hole therein, tabs extending from said flat supporting portion into said slots in said leaves and being turned back upon themselves and having free ends that extend to said supporting portion, one of said free ends having a hole therein, spacer members between said leaf holding members having holes therein, said holes in said binding portions, supporting portions spacer members and free end being so positioned that they are in alignment with each other, means extending through said holes and holding said covers, leaf holding members and spacer members in assembled relationship.

DON M. HARRIS.
